UNITED STATES PATENT OFFICE.

FRANK H. COLE, OF CHELSEA, MASSACHUSETTS.

APPARATUS FOR UTILIZING WASTE HEAT FROM PRODUCTS OF COMBUSTION.

1,181,847.

Specification of Letters Patent.

Patented May 2, 1916.

Application filed September 16, 1914. Serial No. 862,032.

To all whom it may concern:

Be it known that I, FRANK H. COLE, a citizen of the United States, residing at Chelsea, in the county of Suffolk and State 5 of Massachusetts, have invented new and useful Improvements in Apparatus for Utilizing Waste Heat from Products of Combustion, of which the following is a specification.

10 This invention relates to improvements in apparatus for utilizing waste heat from products of combustion.

The object of this invention is to provide an apparatus adapted to be used in connection with boilers or heaters for the purpose of securing from the smoke gases or products of combustion substantially all of the heat units which would normally be discharged as waste through a stack to the air 15 or otherwise, such heat units representing from 40% to 65% of the total number contained in fuel.

Another object of this invention is to provide simple and efficient means for still further reducing the temperature of smoke or gas and in carrying off the smoke and cinders. 20

Still another object of the invention is to provide means whereby the smoke flues and 25 air passages of the apparatus may be kept free from smoke and cinders.

The invention consists in the combination and arrangement of parts set forth in the following specification and particularly 30 pointed out in the claims.

Referring to the drawings: Figure 1 is a longitudinal sectional elevation of a boiler illustrating one form of apparatus embodying my invention. Fig. 2 is a detail sectional plan of the casing containing the smoke and air flues. Fig. 3 is a partial front elevation of a battery of boilers illustrating the manner in which one apparatus 35 may be utilized to take care of the smoke from two or more boilers, portions of said 40 figure being broken away and other parts shown in section. Fig. 4 is a section taken on line 4—4 of Fig. 1.

Like numerals refer to like parts throughout the several views of the drawings.

In the drawings, 5 is a boiler preferably, though not necessarily, of the water tube type of boiler and consisting of a fire box 6 communicating with a combustion chamber 7 from which the products of combustion 55 are discharged through an opening or dis-

charge orifice 8 into a smoke flue 9. In the present case however gases are preferably not discharged directly into the smoke flue 9, but pass through an economizer or what is sometimes called a secondary boiler 10 of the usual and well known construction and adapted to heat water, which is passed through said economizer, by means of pipes 11 and subsequently delivered to the boiler 5 in a partially heated state in order that the efficiency of the boiler may not be reduced when the same is injected therein. After leaving the secondary boiler 10 the smoke flue 9 preferably descends slightly 60 and is connected with a casing 12 preferably containing a plurality of smoke passages or flues 13 and a plurality of air passages or conductors 14 extending longitudinally of said casing and alternating with said smoke 65 passages, said air passages being in close proximity to said smoke passages.

The casing 12 is preferably rectangular in shape and horizontally disposed, while a plurality of partitions 15 extend longitudinally of said casing dividing the same into passages which constitute said smoke and air passages. These partitions are preferably corrugated transversely of their length, said corrugations in the present instance 70 being vertically disposed as at 16. The desired spacing of said partitions is secured by means of bolts 17 arranged transversely of the casing through the side walls 18 and 19 thereof upon which are mounted sections 75 of tubes 20, 20 of the desired lengths which engage opposite faces of the partitions 15. In the preferred embodiment of the invention there are four of said partitions 15 which divide the casing 12 into five passages 21, 22, 23, 24 and 25, the passages 21, 23 and 25 being air passages, while the 80 passages 22 and 24 are smoke passages thereby providing a circulation of air along each side of the smoke passages.

As the flue 9 descends from the heater it is connected preferably through openings 26 and 27 in the top of the casing with the two smoke flues 22 and 24, permitting the gas and smoke from the furnace or boiler to 85 pass longitudinally of the casing 12. The amount of smoke passing therethrough is governed by dampers 22' and 24' adjacent the inlet ends of said flues.

The opposite ends of the flues 22 and 24 90 unite with a common smoke flue 28 which is bent substantially at right angles to form

an elbow 29 extending downwardly and into communication preferably with the sewer, not shown in the drawings, or to any other suitable outlet.

As the smoke or products of combustion from the boiler 5 pass through the casing 12, the greater portion of the heat units contained therein are removed by means of the currents of fresh air which are conducted through the casing in the passages 21, 23 and 25 in the opposite direction to that in which the smoke and gases are being carried through their passages 22 and 24. The corrugations 15 serve to resist the passage of currents of air and smoke and thereby greatly assist the transfer of said units from said smoke to said air. It will be seen by reference to the drawings that the area of the passage 22 and that of the passage 24 when combined produce a flue which is much larger in area than the flue 9, consequently when the smoke and gases enter the larger portion of said flue the speed thereof will be greatly reduced, permitting the greater portion of the cinders and smoke carried thereby to settle to the bottom of said passages 22 and 24.

Air is supplied to the passages 21, 23 and 25 through a cold air supply pipe 30 connected with all of said air passages at a point in said casing adjacent the elbow 29. The amount of air passing through said passages is controlled or regulated by dampers 52 arranged adjacent the inlet ends of said passages.

From the casing 12 the air is conducted through an air conductor 31 into which open all of the passages 21, 23 and 25 and at a point adjacent the flue 9, to the casing 40 of a blower 32 arranged adjacent to the front of the boiler, said blower being preferably operated by an engine 33. A discharge pipe 34 for the blower 32 preferably extends transversely of the boiler or boilers 45 to which said blower is to supply air, said pipe 34 having branches 35, 35 which extend upwardly and connect with the boilers preferably directly beneath the grates 37 thereof.

A protector 38 is provided above the mouths of the pipes 35 to prevent ashes from dropping into the same and shutting off the supply of air, it being understood that any desired number of boilers may be connected with the blower. By arranging the blower 55 and air conductors in the manner hereinbefore described, currents of fresh air will be drawn or impelled by said blower through the passages 21, 23 and 25 in the direction of the arrows "a" in contact with the partitions 15, whereupon said air will absorb more or less of the heat from said partitions radiated from the hot gases or products of combustion which may be passing through the smoke flues 22 and 24, thereby reducing the temperature of said smoke and gases until said currents of air and said gases have reached a temperature substantially uniform. The air heated in this manner will then be drawn by the blower 32 through the conductor 31 into the blower casing from whence it will be forced by said blower through the pipes 35 to the combustion chamber or fire box of the boiler, whereupon the combustion of the gases and fuel therein will be greatly enhanced by reason of the fact that said air has been heated before it is admitted to the fire box.

The smoke passages 22 and 24 are entirely independent of the air passages 21, 23 and 25, consequently there will be no chance or danger of gas and smoke passing through the blower to injure or destroy the same. From the common smoke flue 28 the smoke and gases are carried downwardly through the elbow 29 to the sewer, or any other point desired, but before said smoke and gases are permitted to escape they are first reduced in temperature and treated by being passed through a film or volume of water which is preferably supplied to the flue directly beneath the elbow 29. At this point said flue is slightly reduced in diameter at 39, while just above said reduced portion a disk 40, preferably conical, is rotatably arranged with its base directly downwardly, said disk 40 being secured to the lower end of a shaft 41 rotatably arranged within a sleeve 42, which projects through the outer wall of the elbow and has secured at its outer end a motor 43, preferably a water motor. Said motor 43 is operatively connected to the upper end of the shaft 41.

The motor 43 is adapted to be operated by water which is delivered thereto through a pipe 44 connected to the periphery of the casing of said motor. As the water passes through the motor it is discharged into the sleeve 42 from whence it is delivered to the outer or upper surface of the disk 40, which is rotated by said motor, whereupon the water delivered to said disk will be thrown outwardly by centrifugal force against the inner wall of the flue, within which said disk is arranged, forming a volume of water through which cinders and smoke must pass before they are discharged. Said water then passes downwardly to the discharge outlet for said flue and carries with it any dust or cinders which may have collected within said flue.

By supplying water to the flue, as hereinbefore described, an additional momentum or impulse will be given to the smoke and gases which have passed through the flues 22 and 24 and thus remove impure or obnoxious gases from the smoke or air and discharge the same into the sewer or other suitable receptacles or means supplied for carrying off the same and making room within the passages 22 and 24 for other

smoke and gases to be treated in a like manner. To provide free access to the smoke passages in order to clean the smoke and cinders from the partitions 15, the upper wall 45 of said casing is provided with 5 a plurality of openings 46 which are closed by doors 47 preferably formed in two sections, pivotally mounted upon rods 48 arranged longitudinally of the casing at the upper corners thereof and in the upper ends 10 of reinforcing members 49, preferably angles extending transversely of the side walls 19 of said casing.

A cinder drum 50 is formed along the bottom of the casing 12 communicating with the passages 22 and 24 which catches the cinders coming in contact with the corrugations 16 of the partitions 15 and are deflected thereby to the bottom of the casing. A 15 plurality of gates 51 are arranged at predetermined distances apart along the bottom of said cinder drum by means of which the cinders, which have collected in said drum, may be withdrawn.

While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific application herein shown, but that extensive deviations from the illustrated form or embodiment of the invention may be made without departing from the principles thereof.

Having thus described my invention what I claim and desire by Letters Patent to 40 secure is:

1. An apparatus of the class described comprising a plurality of smoke flues, a plurality of air flues alternating with said smoke flues, corrugated partitions interposed 45 between said smoke and air flues with the corrugations thereof arranged vertically, and doors arranged along the upper and lower walls of said smoke flues adapted to permit access thereto to clean said partitions and remove the cinders from said flues.

2. An apparatus of the class described

having, in combination, a horizontally disposed, rectangular casing, a plurality of vertically disposed partitions extending longitudinally of said casing and adapted to divide said casing into alternate smoke and air passages, corrugations in said partitions extending vertically thereof, a plurality of doors formed in the upper wall of said casing adapted to permit access to said smoke passages to clean the same, and a plurality of slides arranged at the bottom of said casing adapted to permit the withdrawal of cinders and dust from said smoke 60 passages.

3. An apparatus of the class described having, in combination, a rectangular casing, a plurality of vertical partitions arranged longitudinally of said casing adapted to divide the same into alternate smoke 70 and air passages, a plurality of reinforcing members extending transversely of opposite sides of said casing, rods extending longitudinally of and at opposite sides of said casing through the upper ends of said reinforcing members, and a plurality of doors pivotally mounted on said rods adapted to permit access to said smoke passages.

4. An apparatus of the class described having, in combination, a rectangular casing, a plurality of vertically disposed partitions extending lengthwise of said casing adapted to divide said casing into a plurality of alternate smoke and air passages, said casing consisting of a plurality of cinder 80 drums at the bottom thereof communicating with all of the smoke passages of said casing, said drums having openings at the bottoms thereof, said casing also having a plurality of openings at the top constructed 85 and arranged to permit access to all of said passages and means constructed and arranged to impel smoke and air through said passages.

In testimony whereof I have hereunto set 90 my hand in presence of two subscribing witnesses.

FRANK H. COLE.
